UNITED STATES PATENT OFFICE.

WALTER W. RICHARDS, OF PHILADELPHIA, PENNSYLVANIA.

WINDOW-SASH.

SPECIFICATION forming part of Letters Patent No. 351,797, dated November 2, 1886.

Application filed February 11, 1886. Serial No. 191,531. (No model.)

To all whom it may concern:

Be it known that I, WALTER W. RICHARDS, a citizen of the United States, residing in the city and county of Philadelphia, State of Pennsylvania, have invented a new and useful Improvement in Window-Sashes, which improvement is fully set forth in the following specification and accompanying drawings, in which—

10 Figure 1 represents a front view, partially broken away, of a window-sash embodying my invention. Fig. 2 represents a vertical section in line xx , Fig. 1. Fig. 3 represents a horizontal section in line yy , Fig. 1; and Fig. 4 is 15 a sectional view of a detached portion on an enlarged scale.

Similar letters of reference indicate corresponding parts in the several figures.

My invention relates to improvements in 20 window-sashes; and it consists in providing the same with detachable plates and grooved castings pivotally connected, the said plates being secured to the sashes and the castings having attached thereto cords carrying 25 weights, all as hereinafter fully described, whereby the sash may be raised or lowered and rotated when desired.

Referring to the drawings, A represents a window-sash, and B the window-frame.

30 C represents grooves in the inner sides of the window-frame, and in the same are fitted sliding pieces or castings D, to which the sash-cords are attached. The window-sash is pivoted at its sides to said pieces or castings, 35 whereby the sash may rotate thereon, so that either side of the sash may be brought into the room or presented on the outside, whereby it is accessible for purposes of cleansing, glazing, &c.

40 The dividing-strips E are made removable from the window-frame, and when in position are held by bolts F or other fastenings, said

bolts being fitted to the strips and adapted to enter openings or sockets in the sill-piece. When the strips are removed, both upper and 45 lower sashes may be rotated, owing to their pivotal connection with the pieces or castings D. The strips E are employed as weather-strips, and close the joints between the two sashes, and assist in guiding the sash when 50 raised or lowered.

The castings D have grooves in the backs to receive the sash-cords, and cross-pieces a, to which the ends of said cords are held by knots formed on the cords. The sash has secured to 55 its side plates G, in which are horizontal openings or sockets to receive the gudgeons or pivots H, which project horizontally inward from the castings, the front parts, G', of said plates being detachable, whereby access may be had 60 to the pivots, and the latter withdrawn from said sockets, in order to disconnect the sashes from the castings, and thus entirely remove said sashes from the window-frame.

Having thus described my invention, what 55 I claim as new, and desire to secure by Letters Patent, is—

1. The sash A, in combination with the plates G, having detachable front parts, G', and provided with sockets, the grooved casting D, with pivot H, and cords carrying 70 weights, the cords being secured in the grooves of said casting D, all substantially as and for the purpose set forth.

2. The sash A, in combination with the 75 plate G, having detachable front piece, G', and a horizontal socket, the grooved casting D, with pivot H and cross-piece a, and a cord having a weight attached thereto, all substantially as described.

WALTER W. RICHARDS.
